AERIAL ADVERTISING APPARATUS

Filed Feb. 13, 1926

UNITED STATES PATENT OFFICE

EDGAR G. FINLAY, OF SAN FRANCISCO, CALIFORNIA, ASSIGNOR, BY MESNE ASSIGNMENTS, TO AERIAL ADVERTISING COMPANY, INC., A CORPORATION OF NEVADA

AERIAL ADVERTISING APPARATUS

Application filed February 13, 1926. Serial No. 88,033.

This invention relates to improvements in aerial advertising apparatus, the primary object being to provide a simply constructed and inexpensive apparatus which may be readily and easily handled and operated to effectively display advertising matter at a considerable elevation above the ground.

One of the purposes of the invention is to provide an aerial advertising apparatus of the character described wherein a balloon, kite or other aerial vehicle of this nature may be effectively employed to maintain a sign containing suitable advertising matter in a position so that it will be effectively displayed as above described.

The invention further resides in the provision of a structure or sign for supporting advertising subject matter, which structure or sign may be readily attached to the kite, balloon or other aerial device, or to the line leading from the balloon or other aerial device to an anchorage, the said supporting structure or sign being of novel construction and arranged so that it will at all times remain in position to effectively display the advertising matter supported thereon.

Another object is to provide a sign or supporting structure of the character described which will be exceptionally light, strong and durable and which may be made up on comparatively large sizes so that the effectiveness of the advertising display will be enhanced without materially increasing the weight or rendering the apparatus as a whole more difficult to handle and operate.

With the above mentioned and other objects in view, the invention consists in the novel construction and combination of parts hereinafter described, illustrated in the accompanying drawing, and set forth in the claims hereto appended, it being understood that various changes in the form, proportion, size and minor details of construction within the scope of the claims may be resorted to without departing from the spirit or sacrificing any of the advantages of the invention.

Referring to the drawing:

Fig. 1 represents a front elevation of aerial

advertising apparatus constructed in accordance with this invention.

Fig. 2 represents an end elevation of the apparatus shown in Fig. 1.

Fig. 3 represents a perspective view of the apparatus as it will appear when in use.

Fig. 4 represents a top plan view of the sign.

In the embodiment of the invention shown in the accompanying drawing, I have provided a captive balloon generally designated 5, which is employed as a means for supporting a sign or advertising supporting frame 6. The balloon 5 is held by a suitable line 7 extending to the sign and a line 8 extends from the sign to the balloon. As a matter of fact, these lines 7 and 8 may be one continuous line extending through the sign as shown in Fig. 1, or several lines may be secured together so as to have the same effect as one continuous line. While I have shown a balloon as an aerial supporting means for the sign, I may employ a kite, or any other suitable means which will serve the purpose of the balloon or the kite.

The sign 6 is of special construction for the following reasons: First, so that it may be made comparatively large without materially increasing the weight or causing the apparatus as a whole to become clumsy and difficult to operate; second, so that it may be strong and durable as well as light and large; and third, so that it will maintain the desired position to effectively display advertising matter in heavy as well as light winds and will so operate under variable weather conditions.

The sign is composed of a flexible fabric, net work body designated 9, preferably made of cord or like flexible material and with its meshes like that of an ordinary tennis net, but of course said body is of greater size than the ordinary tennis net. Along the lower and upper longitudinal edges of this flexible net body, small stiffening rods 10 and 11 respectively are secured in any suitable manner, said rods being formed of wood, aluminum or any other light, strong substance. Fastened centrally of their ends to said rods 10 and 11 and extending transversely thereof,

are a plurality of small light cross rods 12, 13, 14 and 15, of which the one 12 is the shorter; the one 13 longer than the one 12; the one 14 longer than the one 13 and the one 15 approximately the same length as the one 13. These cross rods are fastened in any suitable manner either by being wrapped with wire or cord or by using other fastening elements and they are spaced apart equa-dis-
10 tantly from one another as shown in Fig. 4.

Guy wires or cords 16 and 17 are fastened to the extremities of the rods 10 and 11 on one side of the net, being fastened or secured in any suitable manner to the ends of the cross
15 rods 12, 13, 14 and 15. The wires 17 extend from certain ends of the members 10 and 11 to the rod 14 and the wires 16 extend from the other ends of the members 10 and 11 to said rod 14. Similar guy wires 18 and 19 are
20 identically arranged on the other side of the net. This bracing arrangement provides a strong and durable sign structure but does not deprive the structure of the desired flexibility.

25 The lines 7 and 8 leading to the balloon may be arranged as shown in Figs. 1 and 2. The line 7 is fastened to a ring 20 to which ring are connected a plurality of flexible stays 21. These stays are fastened to the terminals of the rod 10 and to the terminals of the cross rods 12, 13, 14 and 15, and converge from these points towards the ring. Extending from the ring in alignment with the cord 7 is a cord or line 22 which is joined to the
30 rod 10 to one side of a point centrally of the ends of said rod and at which point the lower cross rod 14 is fastened. Another cord 23, or in fact, a cord which may be considered as an extension of the cord 22, extends up
35 along one side of and through the net body directly to the upper rod 11 and is fastened to said rod at the point where the upper post 14 is secured, this to one side of the center of the net. Another cord 24 constituting an ex-
40 tension of the cord 23 extends from the point where the cord 23 is fastened to the member 11 up to a ring 25 to which it is fastened. Flexible stays 26 corresponding to the stays 21 are connected with the ring and with the
45 upper cross rods as well as the rod 11, in the same manner as are the stays 21. Cords 27, shown in Figure 2, connect correspond-
50 ing ends of the upper and lower cross rods 12, 13, 14 and 15. The line or cord 8 is fas-
55 tened to the ring and is extended up to the balloon. In this way as shown in Figure 1, the cords or lines 8, 24, 23, 22 and 7 are virtually one line extending in alignment directly from the anchorage on the ground through the sign and to the balloon. This line in being fastened to the sign on one side of the vertical median line of the net, disposes the sign off center so that it will be effectively and
60 steadily held in the wind like a weather vane.
65

All tendency of the "flapping" of the sign is eliminated by this offsetting thereof.

As noted, the sign may include letters as shown at 28. These letters may be of cloth or any other material but are preferably of flexible material. Instead of using letters, any other advertising or display means may be employed and supported upon the net work as desired.

70 With the embodiment of the invention as shown in the accompanying drawing, a sign may be made of as great a size as forty feet square or even larger and a comparatively small balloon or kite may be effectively employed to support the sign in a stable manner so that the advertising matter thereon will be plainly visible at the desired elevation from the ground. The special construction of the sign and the bracing thereof makes possible these proportions and also provides for a safe and easy operation or handling of the sign and other rigging under various weather conditions.

75 Any number of cross rods or bracing arrangements as shown at the upper and lower edges of the net work sign may, if desired, be placed between the edges of the sign and this will depend upon the depth or width of the sign.

80 The cords 27 shown in Figs. 1 and 2 constitute tension members extending between the upper and lower parts of the aerial sign structure and serve to limit the separation of the lower and upper stiffening rods 10 and 11 to which the lower and upper longitudinal edges 85 of the network body are attached. By functioning in this manner they control or limit the tension to which the net body 9 may be subjected by the upward pull of the balloon 5 on the anchorage element by which it is secured to the ground.

85 In this manner valuable objects and advantages of the invention are attained in that the sign may, as a result of such expedient, be made of a relatively fragile net but may be caused to satisfactorily operate to display advertising in an effective manner for the reason that means are employed with the net sign supporting structure 9 for holding it in tension and for controlling or limiting the tension within the limits of strength of the net, yet sufficient to hold it taut.

90 I claim:

95 1. Aerial advertising apparatus comprising a net, stiffening rods extending along the upper and lower edges of the net and attached thereto, cross rods extending transversely of said stiffening rods and attached thereto intermediate their ends, stays connecting the ends of said cross rods with said stiffening rods, and an aerial vehicle for supporting said net.

100 2. Aerial advertising apparatus comprising a net, a stiffening rod extending along a horizontal edge of said net and attached

- thereto, a cross rod extending transversely of said stiffening rod and attached thereto intermediate its ends, stays connecting the ends of said cross rod with said stiffening rod, and an aerial vehicle supporting said net.
3. Aerial advertising apparatus comprising a net, a stiffening rod extending along a horizontal edge of said net and attached thereto, a plurality of cross rods of different lengths extending transversely of said stiffening rod and attached thereto intermediate their ends, stays connecting the ends of said cross rods with each other and with said stiffening rod, and an aerial vehicle for supporting said net.
4. Aerial advertising apparatus comprising a net, stiffening rods extending along the upper and lower edges of the net and attached thereto, cross rods extending transversely of said stiffening rods and attached thereto intermediate their ends, stays connecting the ends of said cross rods with said stiffening rods, an aerial vehicle for supporting said net, means for anchoring said vehicle to the ground, and diagonal guys extending from the plane of said cross rods and connecting the ends of said cross rods with said anchoring means.
5. An aerial advertising device, including: an air vehicle; an anchorage element for said vehicle; a net sign incorporated with said anchorage element in such a manner that tension in said element will operate to place tension in said net sign; and means for limiting the tension so placed in said net sign.
6. An aerial sign structure for suspension from an air vehicle, including: a net sign; means for placing tension on said net sign; and means for limiting the tension which may be placed on said net sign to that serving to hold the net sign against flapping under wind action to which it is subjected in the air.
7. An aerial sign structure for suspension from an air vehicle, including: a net sign; means for placing tension on said net sign; and means for limiting the tension which may be placed on said net sign to that serving to hold the net sign substantially flat extending vertically from the upper portion to the lower portion of said net sign.
8. An aerial advertising device, including: an air vehicle; an upper attachment means below said vehicle; a display structure attached to said upper attachment means, said structure comprising an upper frame, a lower frame, tension members extending between said upper and lower frames, and a display fabric extended between said upper and lower frames; a lower attachment means below said lower frame and attached thereto; and an anchor member extending downward from said lower attachment means to a point of anchorage.
9. An aerial advertising device, including: an air vehicle; an upper attachment means
- below said vehicle; a display structure attached to said upper attachment means, said structure comprising an upper frame, a lower frame, said upper and lower frames lying in horizontal planes, tension members extending between said upper and lower frames, and a display fabric extended between said upper and lower frames; a lower attachment means below said lower frame and attached thereto; and an anchor member extending downward from said lower attachment means to a point of anchorage. 70
10. In an aerial advertising device, the combination of: an air vehicle; an anchorage element for said vehicle; a sign incorporated with said anchorage element in such a manner that tension in said element will operate to place tension in said sign; and flexible means for limiting the tension so placed in said sign. 80
